ALFRED VISCHER, JR., OF RIDGEWOOD, NEW JERSEY, ASSIGNOR, BY MESNE ASSIGNMENTS, TO THE FINANCIAL PRESS COMPANIES OF AMERICA, OF BOSTON, MASSACHUSETTS, A TRUST OF MASSACHUSETTS

TYPE WHEEL MOUNTING FOR PRINTING TELEGRAPHS

Application filed August 28, 1930. Serial No. 478,532.

My invention relates to a receiver for printing telegraph system, and more particularly to an improved means for mounting the printing wheel on its shaft.

5 The invention will be understood by reference to the following description, taken in connection with the accompanying drawing, in which Fig. 1 is a front elevation of sufficient parts of a receiver to illustrate the relation of the printing wheel mechanism thereto: Fig. 2 is a transverse section on the plane of the line 2—2 of Fig. 1; Fig. 3 is a vertical section on the plane of the line 3—3 of Fig. 2 and Fig. 4 is a horizontal section on 10 the plane of the line 4—4 of Fig. 2. Similar reference numerals indicate similar parts in the several views.

In the operation of a printing telegraph receiver it is desirable that there shall be a 20 fixed printing position for the wheel as otherwise the printed characters will not be in alinement. As the operation of the machine is very rapid, there is apt to occur an overthrow of the printing wheel when its 25 shaft is located by the escapement 5. The present invention has been designed to insure a fixed and definite printing position of the wheel should there be either an overthrow or insufficient rotation of the wheel with respect 30 to the shaft.

35 Telegraph receivers of the type to which the present invention may be applied, are well known. For an understanding of the invention I have illustrated certain parts of a typical receiver, in which the numeral 1 designates the base and parts of the frame of the machine.

Supported in bearings in the upper portion of the end plates is a shaft 2 driven by a friction clutch 3, the driving member of which is a gear 4. Rotation of shaft 2 is controlled by an escapement, part of which is indicated by the wheel 5. Keyed on shaft 2 for rotation therewith, but slidably mounted thereon, so as to be moved back and forth, is a printing wheel 6 having fixed to its periphery the characters to be printed. The construction is such that at each operation of a polarized magnet, not shown, the escapement wheel 5 will permit shaft 2 to rotate,

and the printing wheel to be set, as usual in machines of this type, and described, for example, in U. S. patent to G. S. Conger, No. 1,178,215, granted April 4, 1916. Surrounding the shaft 2 and free thereon is a bushing 7, providing a bearing for the printing wheel. This bushing is formed with the grooved portion 7' adapted to receive the arms 8 of a bracket extending from a carriage 9, slidably mounted on a shaft 10. 55 Any desired or suitable mechanism may be employed for imparting a step-by-step movement to the printing wheel along its shaft, such, for example, that described in said patent. I have shown, however, part 60 of a mechanism described in a companion application filed August 28, 1930, Serial No. 478,531. This comprises two parallel arranged racks, one of which 11, is here shown. Pivoted independently of each other on carriage 9 are pawls, one of which 11' is here shown, which engages the teeth of the racks. The pawls are held normally in engagement 65 with the racks by springs 12. The construction is such that the racks are alternately 70 moved longitudinally in the same direction to effect the desired movement of the printing wheel.

To carry out the object of the present invention, shaft 2 is formed with a V-shaped 75 groove 2' adapted to receive a spline 13 having its lower part wedge-shaped to correspond to the walls of said groove. The upper part of the spline is slotted, as shown in Fig. 3, to receive a spring 14 clamped 80 between the walls of the slot by a screw 15. This spring at one end is securely fastened by a screw 16 to the side of the printing wheel, and at its other end is in engagement 85 with the under side of a groove in an eccentric 17, adjustably secured to the side of the printing wheel. By adjusting the eccentric 17, the tension on spring 14 may be varied.

The spline 13 is thus supported on spring 14 so as to be held in frictional engagement 90 with the walls of the V-shaped groove 2' at all times. In normal position the lower edge of the spline will be seated in the base of the groove 2'. Should this normal position be disturbed by either an overflow or insuffi-

cient rotation of wheel 6 to properly set the wheel 6 in printing position, the pressure exerted on the spline by reason of the tension of spring 14 will automatically cause 5 the wedge-shaped portion of the spline to bear against the walls of the groove to thereby bring the printing wheel to the position that it should assume to assure perfect alignment of the printed characters.

10 What I claim is:

1. In a printing telegraph receiver the combination of a printing wheel, a shaft on which said wheel is mounted and means for rotating the same, said shaft having a longitudinal groove therein, a spline fitting in said groove, and means resiliently connecting said spline to said wheel to effect automatic adjustment of said spline in the groove of said shaft.
- 15 2. In a printing telegraph receiver the combination of a printing wheel, a shaft on which said wheel is mounted and means for rotating the same, said shaft having a longitudinal groove therein, a spring secured to the side of said wheel and a spline supported on said spring, said spline having a surface adapted to be seated in said groove and held therein by said spring.
- 20 3. In a printing telegraph receiver the combination of a printing wheel, a shaft on which said wheel is mounted and means for rotating the same, said shaft having a longitudinal groove therein, a spring secured to the side of said wheel, a spline supported on said spring, said spline having a surface adapted to be seated in said groove and held therein by said spring, and means for adjusting the tension of said spring.
- 25 4. In a printing telegraph receiver the combination of a printing wheel, a shaft on which said wheel is mounted and means for rotating the same, said shaft having a longitudinal V-shaped groove therein, a spring fixed to the side of said wheel, a spline supported on said spring, said spline having a wedge-shaped section adapted to be seated in said groove, and means for adjusting the tension of said spring.
- 30 5. In a printing telegraph receiver the combination of a rotatable shaft, a printing wheel mounted on said shaft, said shaft having a longitudinal groove wider at its open end than at its closed end, a spline fitting in said groove and engaging the walls of said groove, and a resilient mounting on said wheel for said spline.

Signed at New York, in the county of New York and State of New York this 26th day of August A. D. 1930.
